UNITED STATES PATENT OFFICE.

MERRITT GALLY, OF NEW YORK, N. Y.

MECHANICAL MUSICAL INSTRUMENT.

SPECIFICATION forming part of Letters Patent No. 331,747, dated December 1, 1885.

Application filed July 11, 1884. Serial No. 137,391. (No model.)

To all whom it may concern:

Be it known that I, MERRITT GALLY, a citizen of the United States, residing in the city of New York, county of New York, and State of New York, have invented new and useful Improvements in Musical Instruments, of which the following is a specification.

In the accompanying drawings, Figure 1 is a transverse sectional view of an organ-action embodying my invention, showing a number of parts and their combinations, and Fig. 2 is a detached view of the combined stop and valve apparatus of the action, which are cut away in Fig. 1.

15 In pipe-organs, in which the length of the range of the pipes is usually much longer than the length of the manual key-board, pneumatic actions operated by means of the manual are quite common; but in reed-organs, in 20 which the reeds may all be placed within a space no larger than the manual, the construction is confined to push-pins, being much cheaper than radiating pneumatic tubes.

There would be advantages gained by the 25 use of pneumatic actions in reed-organs operated only by manuals, provided cheap construction could be secured, as the keys of the manual would be more easily operated and the movement of the valves more sensitive. The 30 advantages are greater when the instrument is to be operated by means of the manual or mechanically at will.

The drawings show a construction which provides a simple and effective pneumatic action, so constructed and arranged as to lie, when desirable, entirely within the range of the manual, requiring no radiating tubes for the manual-connections. This action may be used equally well for either an organ operated 35 by manual only or for an organ operated mechanically, or operated mechanically or manually.

Fig. 1 represents an organ provided with three full ranges of reeds, the reed-boards V V' containing one range, the reed-boards R R' containing another range, and the reed-boards X X' containing a third range. The pairs of reed-boards, as V V', contain the reeds of the scale arranged alternating in their progression 40 from one board to the other, so that each valve-board has the space of two finger-keys to each

reed of its reed-board, to accommodate the pneumatic motor, and still the entire range of reed is brought within the range of the manual.

55 The pneumatic motors and sounding-valves, when constructed as shown and contained within the air-chest, as A, are similar in most respects to those I have already described in former specifications. Their arrangement differs in that one half of the action is in ordinary position, while the other half is inverted, or placed facing the other. The line of the vent-tubes which operate the pneumatic motors for the valves of the set of reeds V V' are 60 stopped off by the line of operating-valves 1. The ducts from these valves alternately lead to the motors of the upper and lower part of the action, the ducts for the lower part of the action passing down through the partition N, 65 as shown by the dotted lines. The valves for the sets of reeds R R' and X X' are operated in similar manner by means of the lines of operating-valves 2 and 3. It will be seen that each set is independent in itself, and is operated by its independent line of operating-valves. This obviates the necessity of using 70 mutes or other ordinary stops. To stop off any set, it is only necessary to render inoperative its set of pneumatics.

75 The operating vent-valves 1 2 3 are operated by means of the lifting-hooks a e f, which are pivoted to the lifting bar or lever D, said hooks and lever constituting the valve-lifter. One end of the bar D connects with the finger-key K, and if the instrument is intended to be operated mechanically or automatically the other end of bar D connects with an automatic or mechanically-operated pneumatic motor, T, connecting through tube P with the tracker-range T' and music-sheet S'. The tracker-range is shown providing for the connection 80 of one half the range of tubes on one side of the tracker T'. The other half of the range of tubes connect with the opposite side of the tracker T', and therefore are not in view in the drawings.

85 To render inoperative any one of the three ranges of the organ, I simply render inoperative its line of hooks a, e, or f, as the case may 90 be. For this purpose I provide each line of hooks with a pivoted eccentric-rod, z, which,

being turned on its pivot, throws the hooks out of range of the vent-valves, as shown by the dotted lines at *a*.

In order to render different parts of any range inoperative independently of the other parts, I divide the eccentric-rod, as to its length, into any number of parts desirable, operating each part separately. The operating devices for this stop action are shown in Fig. 2, being cut away by the section in Fig. 1.

Two means for the movement of eccentric-rod *z* are shown in Fig. 2, one for operating by hand in connection with the manual key-board, and the other to act pneumatically in connection with the automatic action. From each side of the eccentric-rod *z* projects a lever, to which are connected the pneumatics *n* and *m*, one to throw the stop on, the other to throw it off. These pneumatics are to operate in connection with the automatic action.

For operating the stops by hand, I either connect the pneumatics *n* and *m* with finger-keys or use the cam *L*, connected to an ordinary draw-stop. A pin projecting from the side of the tilting-lever of eccentric-rod *z* operates in the cam. The cam, having a reciprocating movement, operates the lever. The ends of the cam are open, so that whether the draw-stop is out or in the pneumatics can act freely on the levers. The bellows *E F G* connect with chambers *A B C*, and also with the pneumatic action *T*. The manual-key *K* lifts one end of bar *D*. The pneumatic *T* lifts the opposite end of bar *D*. The operation of the instrument is the same, either end of the bar being lifted.

To limit the movement of the valve-levers in the chests *A B C*, I usually employ a right-angle wire hanger projecting from the valve-board, with a set-screw and button screwing into the lever for limiting the movement, the button striking the right-angle projection of the wire hanger. In the present case I show only a right-angle wire hanger. A screw-thread is cut on the end of this hanger, so that it can be screwed more or less into the valve-board. This forms a simple and cheap stop for the purpose, and is much cheaper than the other construction. The actions are placed either horizontal or vertical, as shown.

What I claim as my invention is—

1. In an organ-action, two valve-boards facing each other and provided with pneumatic valves alternately leading to the two valve-boards.

2. The bar or lever, as *D*, provided with lifting-hooks, as *a e f*, for operating different sets of vent-valves, substantially as specified.

3. The combination, with the vent-valves, as 1 2 3, of the manual-key *K* and the operating lever and hooks, substantially as specified.

4. The combination, with the vent-valves, as 1 2 3, of the lever *D*, provided with its operating-hooks, and a pneumatic motor, as *T*, substantially as specified.

5. The combination, with the pneumatic vent-valve, as 1, of the operating lifting-hook and a device for throwing the hook out of operating connection with the valve, substantially as specified.

6. The combination, with a series of lifting-hooks for operating pneumatic vent-valves, of the cammed rock-shaft *z*, substantially as set forth.

7. The combination, with a series of lifting-hooks for operating a series of pneumatic vent-valves, of the cam rock-shaft *z*, operated by means of pneumatics, as *n* and *m*, substantially as specified.

8. The combination, with the series of valve-operating hooks and devices for throwing the hooks out of connection with the valves, of a hand draw-stop for operating the throw-off.

9. The combination, with the cammed rock-shaft *z* and its lever projections, of the reciprocating cam *L*, substantially as and for the purpose specified.

10. The combination, with a vent-valve and a single lifter for the same, of a manual-key 90 and a pneumatic motor, both operating on the lifter.

11. The combination, with a vent-valve and a lifter for the same, of a manual-key operating on one end of said lifter, and a pneumatic 95 motor operating on the other end thereof.
